UNITED STATES PATENT OFFICE.

SAMUEL EVERETT FINLEY, OF ATLANTA, GEORGIA.

STREET-PAVEMENT.

No. 922,687.

Specification of Letters Patent.

Patented May 25, 1908.

Application filed June 16, 1908. Serial No. 437,729.

To all whom it may concern:

Be it known that I, SAMUEL EVERETT FINLEY, a citizen of the United States, residing at Atlanta, in the county of Fulton and State 5 of Georgia, have invented certain new and useful Improvements in Street-Pavements; and I do declare the following to be a full, clear, and exact description of the invention, such as will enable others skilled in the art to 10 which it appertains to make and use the same.

My invention relates to improvements in street pavements, especially of the wooden block type.

15 It has for its object to provide such a pavement capable of extended wear and durability, provision being made for avoiding dampness, and the preservation of the life of the individual block members of the pavement. Also, to carry out these purposes in a 20 simple, economical and effective manner.

With these and other objects in view, the invention consists of certain novel features of construction, combination and arrangement of parts as will be more fully described and particularly pointed out in the appended claims.

35 In laying street pavement blocks, as commonly practiced, they are provided at suitable intervals with recesses which are usually filled with a composition, the dominant ingredient or element of which is pitch or tar, but said recesses are not always closed by said composition, for the reason that the latter responds more freely to expansion and contraction than the wooden blocks employed in such pavement so that at periods when contraction is taking place, openings or spaces result between the blocks and the 40 composition, allowing water and dampness to drain or work downwardly into said spaces and under said blocks, which openings are, however, later closed by the composition, but said water having no outlet, the resulting 45 dampness produces what is termed "buckling."

I have found, however, that by introducing rubber strips, or a resilient substance, arranged both parallel with the curb and transversely of the pavement blocks, the aforesaid objections are wholly avoided, for the reason that the elastic material, or strips, will expand and contract absolutely with the corresponding action of the wooden blocks of 55 the pavement and thus keep all otherwise resulting openings closed, and accordingly

prevent any "buckling" action of the pavement, or of any block pavement characterized by the distinctive features of my invention.

In the accompanying drawings, illustrating the preferred embodiment of my invention, Figure 1 is a plan view of a section of a wooden street pavement produced in accordance with the invention; Fig. 2 is a transverse sectional view on the line $y-y$ of Fig. 1; Fig. 3 is a cross sectional view on the line $x-x$ of the same figure; Fig. 4 is a detail view of one of the pavement blocks; Fig. 5 is a modification thereof; and Fig. 6 is an additional modification of the pavement-block, disclosing the same with a single longitudinal groove in its underside.

In practicing my invention I first suitably place or prepare a concrete base 1 and upon 75 this lay a "cushion" or layer of sand, 2, or mortar bed comprised of cement and sand of suitable depth, and superpose or lay upon the latter the pavement-blocks, 3, preferably of wood and treated with creosote or 80 other preservative and of the general outline shown, or in lieu of wooden blocks bricks may be used, or the blocks may be other material. Said blocks, 3, are each provided, when of the usual brick size, with duplicated 85 spaced-apart passages, or recesses, 5, arranged in its bottom surface, but when of less dimensions than a standard brick, or half size, simply a single recess or passage is provided therein as will be readily understood. 90 It will be understood that these recesses or passages which extend transversely through the individual blocks are arranged in communication with each other and thus form continuous passages throughout both the transverse and longitudinal area of the pavement 95 constituted of said blocks, as will be readily understood. The purpose of these passages, primarily, is to provide for the conducting away of water draining through the joints 100 between the blocks of the pavement, and for ventilation for keeping said passages free of dampness.

Rubber or elastic strips, 6, are interposed between adjacent blocks of the pavement at 105 certain intervals throughout the latter, also additional like strips or partitions, 6^a, are arranged between the pavement blocks and the curbing, the purpose of which elastic or resilient strips of material is, as above stated, 110 to allow of the ready contraction and expansion of the block-courses under the varying

conditions of the atmosphere and the elements, as will be readily appreciated, for avoiding the other resulting spaces or openings between said block as against the draining downwardly through the joints of the blocks, as also previously stated.

Metal ventilating tubes, 7, are also arranged just under said rubber strips and have lateral openings, 8, registering with the 10 passages or recesses in the blocks, 3. Said ventilating tubes may be of any preferred outline and suitably secured in place, and may be also arranged at other intervals in the pavement, intermediate of the adjoining 15 blocks, at which points the rubber strips are not used, if so desired. The openings in these ventilating tubes may be of the form or outline shown, that is, angular, or may be rounded at their upper edges as desired. 20 Also additional like ventilating and draining tubes 9 are disposed or arranged longitudinally, or in the direction of the length of the street or pavement, alongside of the curbing and at a point below the lower edges or ends 25 of the pavement blocks adjacent to said curbing. These longitudinally disposed tubes suitably communicate with the aforesaid tubes 7, and are designed to provide for additional ventilation and also for draining pur- 30 poses, having their delivery or discharging ends, leading to the catch-basin, as commonly used in streets for receiving and conducting away the accumulated drainage and with upright air pipes 9' arranged adjacent 35 to the curbing with their upper ends opening above the general surface and bent laterally to permit the air to pass in and prevent rain, from entering. These pipes 9' are preferably arranged at the junction of the pipes 7 with 40 the pipes 9.

From the foregoing, as has already been set forth, it will be noted that I have provided a street pavement of the general type described, which is characterized for its sim- 45 plicity in construction and which may be readily laid and at little expense, besides possessing the qualities of durability and cheapness.

From the foregoing description, taken in 50 connection with the accompanying drawings, the construction and operation of the invention will be readily understood without requiring a more extended explanation.

Various changes in the form proportion 55 and the minor details of construction may be resorted to without departing from the principle or sacrificing any of the advantages of the invention as defined in the appended claims.

Having thus described my invention, what

I claim as new and desire to secure by Letters Patent, is:

1. A street pavement of the class described comprising blocks having registering openings or passages in their lower faces and ventilating tubes open to the atmosphere and arranged thereunder and having spaced lateral openings throughout their length registering with the passages in said blocks. 65

2. A street pavement of the character de- 70 scribed, embracing blocks having registering passages or recesses in their under surfaces, resilient strips of material arranged between the adjacent block courses, and ventilating tubes arranged in vertical alinement with 75 said resilient means.

3. A street pavement of the character de- 80 scribed, embracing wooden blocks having registering passages or recesses in their lower surfaces, strips of resilient material inter- 85 posed between adjacent block courses and said block courses and the curbing, and ventilating tubes having lateral openings registering with passages or recesses in said blocks. 95

4. A street pavement of the character de- 90 scribed, comprising block members having registering openings or passages in their lower surfaces extending lengthwise of said blocks and ventilating tubes open to the at- 100 mosphere and having lateral openings register- 105 tering with said passages of said blocks.

5. A street pavement comprising surface 110 blocks having passages in their lower faces pipes arranged therebeneath, and provided 95 with longitudinally spaced lateral openings registering with the openings in said blocks, similar pipes extending longitudinally on op- 115 posite sides of the pavement and commun- 120 icating with said transverse pipes and means 100 for admitting air to said pipes.

6. A street pavement comprising surface 125 blocks having passages in their lower faces pipes arranged therebeneath and provided 110 with longitudinally spaced lateral openings 130 registering with the openings in said blocks, similar pipes extending longitudinally on op- 135 posite sides of the pavement and commun- 140 icating with said transverse pipes, and up- 145 right pipes connected with said longitudinal 11 pipes and having their upper ends projecting 150 above the surface of the pavement and bent laterally.

In testimony whereof I have hereunto set 155 my hand in presence of two subscribing 160 witnesses:

SAMUEL EVERETT FINLEY
